UNITED STATES PATENT OFFICE

162,507

VEHICLE INTERIOR LIGHTING AND VENTILATING UNIT

Albert L. Arenberg, Highland Park, and Edward C. Zimmerman, Winnetka, Ill., assignors to Patent License Corporation, Chicago, Ill., a corporation of Illinois

Application June 1, 1948, Serial No. 146,714

Term of patent 14 years

(Cl. D48—32)

To all whom it may concern:

Be it known that we, Albert L. Arenberg and Edward C. Zimmerman, citizens of the United States, residing at Highland Park, in the county of Lake and State of Illinois, and at Winnetka, in the county of Cook and State of Illinois, respectively, have invented a new, original, and ornamental Design for a Vehicle Interior Lighting and Ventilating Unit, of which the following is a specification; reference being had to the accompanying drawing forming a part hereof.

In the drawing:

Fig. 1 is a front elevational view of a vehicle interior lighting and ventilating unit showing our new design,

Fig. 2 is a top plan view thereof, and

Fig. 3 is a side elevational view.

The dominant features of our design reside in the portions shown in solid lines.

We claim:

The ornamental design for a vehicle interior lighting and ventilating unit, substantially as shown and described.

ALBERT L. ARENBERG.
EDWARD C. ZIMMERMAN.
